UNITED STATES PATENT OFFICE.

OREN WILLIAMS, OF GOVERNEUR, NEW YORK.

SNOW-PLOW.

SPECIFICATION forming part of Letters Patent No. 400,154, dated March 26, 1889.

Application filed November 27, 1888. Serial No. 291,983. (No model.)

To all whom it may concern:

Be it known that I, OREN WILLIAMS, of Gouverneur, in the county of St. Lawrence and State of New York, have invented a new 5 and Improved Snow-Plow, of which the following is a full, clear, and exact description.

My invention relates to an improvement in snow-plows, and has for its object to provide a plow of simple and durable construction 10 which will expeditiously remove the snow from the track, leaving a solid compact wall at each side; and the further object of the invention is to transport the snow as removed to quite a distance at one side of the track.

15 The invention consists in the novel construction and combination of the several parts, as will be hereinafter fully set forth, and pointed out in the claims.

Reference is to be had to the accompanying 20 drawings, forming a part of this specification, in which similar figures of reference indicate corresponding parts in all the views.

Figure 1 is a side elevation of the device. Fig. 2 is a central vertical longitudinal section. Fig. 3 is a partial plan view; and Fig. 25 4 is a transverse vertical section taken on line xx of Fig. 2, illustrating the relative position of the horizontal and vertical conveyers.

In carrying out the invention the body 10 30 of the snow-plow is constructed similarly to a box-car and is mounted upon suitable trucks. The box-body 10 is adapted for the reception of an engine, (which is not illustrated in the drawings,) the driving-shaft 10^a thereof only 35 being shown.

From each side of the box-body arms 11 are forwardly projected, as best shown in dotted lines, Fig. 1, and a second or outer frame is constructed at each side of the body, the same 40 consisting of metal arms 12, extending parallel with the main-frame arms 11 from the outer extremity of said arms to a point at or near the center of the box-like portion of the body. The outer-frame arms 12 are held a 45 distance from the main arms 11 by studs or posts 14, intervening, respectively, the forward extremities of the outer and inner arms and the inner extremity of the outer arm and the box-like body.

50 Between the inner body-arms, 11, a wheel, 15, is journaled, consisting of a drum, 16, mounted upon a suitable axle, 17, the said

axle being journaled in both the outer and inner arms, 11 and 12, as best illustrated in Fig. 3.

From each end of the drum 16 an annular flange, 18, is upwardly projected, and the said wheel is divided into a series of pockets, 19, through the medium of transverse semicircular partitions 20, extending from end to end 60 of the drum and secured to the flanges in any approved manner. The partitions 20 are made to terminate a slight distance from the outer edge of the flange, as best illustrated in Fig. 2, and the said partitions are so located that 65 their concave faces will be in direction of the revolution of the wheel.

In front of each of the partitions 20 a radial slot, 21, is produced, the center of the circle of which slots is immediately above the 70 partitions, at which point the upper ends of discharge-plates 22 are pivoted, one plate being provided for each pocket. The free ends of the plates 22 are provided with pins 23 integral therewith, which pins extend outwardly 75 parallel with the longitudinal face of the plates through the several slots 21, as best illustrated in Figs. 1 and 2.

A trip-plate, 24, is rigidly attached to the inner face of each of the frame-arms 11, which 80 plate is provided with a cam-face, 25, illustrated in dotted lines, Fig. 2, and extends upward above the horizontal plane of the drum portion of the wheel from a forward point, *a*, to a rear point, *b*, the point *a* being so located 85 that when the partitions reach the same they will have assumed virtually a vertical position, and the point *b* is so placed that the said partitions when reaching the said point will have virtually assumed a horizontal position, 90 as is shown in Fig. 2. The cam-face 25 of the trip-plate is curved, which curve, commencing at *a*, is gradually swelled to the rear and carried sharply down to the point *b*.

Between the wheel and the box-body 10 an 95 essentially T-shaped tubular casing, 26, is located, the horizontal member whereof constitutes the base. The upper member, which intersects the horizontal member, is vertical a portion of its length only, and is then carried at an inclination outward above the box-like body and beyond the same.

In the horizontal member of the casing 26 two screw conveyers, 27 and 28, are held to

revolve, one conveyer being formed with a right-hand pitch and the other with a left-hand pitch. The inner ends of the two conveyers are stopped at each side of the center 5 of the horizontal member of the casing, and between the approaching ends of the two horizontal conveyers a short vertical conveyer, 29, is journaled in the casing, which latter conveyer extends upward within the tubular section 10 of the casing. To the upper end of the vertical conveyer 29 a second conveyer, 30, is hinged, the latter conveyer being made to project upward within the inclined portion of the casing to the top thereof, at which point the 15 shaft of the conveyer is journaled in suitable bearings, 31. Upon the outer end of each of the horizontal conveyers 27 and 28 a spur-gear, 32, is secured, and a pulley, 33, the same being located between the inner and outer 20 arms, 11 and 12.

The drive-shaft 10^a is provided at each end with a large pulley, 34, and a smaller pulley, 35, the pulleys 35 being belted to the pulleys 33, located upon the horizontal conveyer- 25 shafts, as best illustrated in Figs. 1 and 3.

The shaft 17 of the wheel 15 is provided near each extremity, between the arms 11 and 12, with a spur-gear, 36, which spur-gear meshes with a pinion, 37, secured to a spindle, 38, 30 journaled between the arms 11 and 12, as best shown in Fig. 3, the said spindle being also made to carry a gear, 39, slightly smaller than the wheel-gear 36, which gear 39 meshes with the gear 32, secured to the horizontal conveyer-shafts. This arrangement of gearing 35 is designed to admit of a rapid motion of the lower conveyers and a comparatively slow revolution of the wheels.

The upper vertical and connected inclined 40 conveyers are adapted to be revolved at least once and a half or twice as fast as the two lower or horizontal conveyers, and to that end upon the lower extremity of the vertical conveyer-shaft a bevel-gear, 40, is secured, 45 meshing with a second bevel-gear, 41, secured to one end of a shaft, 42, journaled longitudinally beneath the plow, the rear end of which shaft is provided with a similar bevel-gear, 43. Through the latter bevel-gear a connection 50 is made with the drive-shaft 10^a, the same being effected by journaling a shaft, 44, beneath the box-body 10, which shaft 44 is provided with a bevel-gear to mesh with the gear 43, and a pulley, 45, belted to the larger pulley, 34, of the drive-shaft 10^a, as illustrated in 55 Fig. 1.

A hopper, 46, is attached to the forward side of the casing 26, which hopper extends from side to side of the main frame of the 60 plow, and communicates with the horizontal and vertical portions of the said casing. The forward end of the hopper is open and faces the wheel.

In operation, as the plow is carried forward 65 through the bank of snow, the discharge-plates of the forward pockets will be forced

inward by the snow in contact with the drum and the snow gathered into the said pockets as the wheel revolves, and as the said pockets are carried upward the pins 23, attached 70 to the ends of the discharge-plates 22, are brought in contact with the cam-surface of the trip-plate 24, and as the pockets are carried farther inward the discharge-plates are elevated gradually until the pins 23 are 75 brought in contact with the outer edge of the slot 21. The snow is at this point discharged into the hopper 46, as illustrated in Fig. 2. After discharging the snow into the hopper the discharge-plates remain in an outward position—that is, with their pins in the outer ends of the slots—until again pressed inward by the snow, as previously described. Thus the snow is continuously delivered from the several pockets of the wheel into the hopper and 85 upon the several horizontal conveyers and the lower portion of the vertical conveyer. The horizontal conveyers carry the snow from the sides of the plow and deliver the same to the vertical conveyer, from which it is passed to the 90 inclined conveyer and delivered by the latter conveyer a distance beyond the side of the track. As the inclined and vertical conveyers are made to revolve at a much greater speed than the horizontal conveyers, they are 95 enabled to carry off all the snow delivered by the latter without inconvenience or choking.

If in practice it is found desirable, the gearing contained between the arms 11 and 12 may be inclosed by any suitable form of casing. 100

I desire it to be distinctly understood that I do not confine myself to the mechanism illustrated for driving the snow-wheel and conveyers, as any other well-known or approved means may be employed without departing from the spirit of the invention. 105

Having thus described my invention, I claim as new and desire to secure by Letters Patent—

1. In a snow-plow, the combination, with a 110 pocketed wheel, of horizontal conveyers and an essentially vertical conveyer located between the horizontal conveyers, substantially as shown and described.

2. In a snow-plow, the combination, with a 115 pocketed wheel, of horizontal conveyers arranged end to end and an essentially vertical conveyer between the opposing ends of the said horizontal conveyers, substantially as and for the purpose specified. 120

3. In a snow-plow, the combination, with a 125 pocketed wheel, of horizontal conveyers arranged end to end, a vertical conveyer located between the ends of the horizontal conveyers, and an inclined conveyer hinged to and driven from the vertical conveyer, as and for the purpose specified.

4. The combination, with a pocketed wheel and discharge-plates pivoted in the pockets of said wheel, of horizontal conveyers arranged end to end, one having a right-hand and the other a left-hand pitch, a vertical 130

conveyer journaled between the approaching ends of the horizontal conveyers, an inclined conveyer attached to and driven from the vertical conveyer, and a hopper adapted to receive the contents of the pockets and deliver the same to the conveyers, substantially as shown and described.

5. The combination, with a pocketed wheel, a discharge-plate pivoted in each of the pockets, provided at its free end with outwardly-extending pins, and a stationary trip-plate provided with a cam-surface adapted for contact with said pins, of horizontal conveyers arranged end to end, one having a right-hand 10 and the other a left-hand pitch, a vertical conveyer journaled between the approaching ends of the horizontal conveyers, an inclined conveyer attached to and driven from the vertical conveyer, and a hopper adapted to receive the contents of the pockets and deliver the same to the conveyers, substantially as shown and described.

6. The combination, with the frame of a snow-plow, a wheel journaled in the forward 25 end of the frame, provided with end flanges having radial slots therein, transverse partitions located at the rear of each slot, dividing said wheel into pockets, a discharge-plate pivoted in each pocket above the partitions, 30 and pins secured to the free ends of the plates

and passing through said slots, of a stationary trip-plate attached to the frame, provided with a circular upper cam-surface adapted for contact with the pins of the discharge-plates, substantially as shown and described. 35

7. The combination, with the frame of a snow-plow, a wheel journaled in the forward end of the frame, provided with end flanges having radial slots therein, transverse partitions located at the rear of each slot, dividing said wheel into pockets, a discharge-plate pivoted in each pocket above the partitions, 40 and pins secured to the free ends of the plates and passing through said slots, of a stationary trip-plate attached to the frame, provided with a circular upper cam-surface adapted for contact with the pins of the discharge-plates, approaching horizontal conveyers 45 journaled to the rear of the wheel, a combined vertical and inclined conveyer journaled between the approaching ends of the horizontal conveyers, and a hopper adapted to receive the snow from the discharge-plates and deliver the same to the conveyers, substantially as and for the purpose specified.
